UNITED STATES PATENT OFFICE.

GEORGE C. HOCKENBERGER, OF BRIDGEPORT, CONNECTICUT, ASSIGNOR TO POOLE ENGINEERING AND MACHINE COMPANY, OF BALTIMORE, MARYLAND, A CORPORATION OF MARYLAND.

CENTER HOUSING FOR WASHING MACHINES.

Application filed August 16, 1923. Serial No. 657,659.

To all whom it may concern:

Be it known that I, GEORGE C. HOCKENBERGER, a citizen of the United States, residing at Bridgeport, in the county of Fairfield and State of Connecticut, have invented certain new and useful Improvements in Center Housings for Washing Machines; and I do hereby declare the following to be a full, clear, and exact description of the invention, such as will enable others skilled in the art to which it appertains to make and use the same.

My invention relates to center housings for washing machines.

Among the objects of my invention are:— To provide center housings for washing machines which comprise means for applying power at will to the cylinder or other structure which ordinarily washes the clothes and which further comprise means for applying power at will to drive in either direction the wringer or other appliance which is used to dry the clothes after same have been washed.

To provide a center housing for washing machines having a revolving element with which the cylinder that washes the clothes can be readily coupled.

To provide a center housing for a washing machine having efficient means for packing the revolving element that drives the washing cylinder so that suds may not find egress from the suds container into said center housings.

To provide a center housing for a washing machine so constructed and arranged that the parts may be readily assembled, readily inspected and readily lubricated.

These and further objects of my invention will become apparent in the following specification, reference being had to the accompanying drawings, and the novel means by which said objects are effectuated will be definitely pointed out in the claims.

In the drawings:—

Figure 1 is a plan view of my improved center housing.

Fig. 2 is a section of the housing shown in Fig. 1 taken along the line 3—3 in said figure looking in the direction of the arrows.

Fig. 3 is a section of the housing shown in Fig. 1 taken along the line 2—2 in said figure looking in the direction of the arrows.

In this figure, the pin 39, lever 40 and handle 42 are shown dotted to show their relation to 55 the clutch member 38 and the handle 27 is omitted.

In the drawings:—

5 represents a part of the side of the suds container which may be of any approved 60 shape and contain a cylinder or other mechanism for washing clothes which is to be connected to the driver 6. The driver 6 is mounted on the shaft 7 and the latter is revolvably mounted in the sleeve 8. A gland 65 9 is secured to the sleeve 8 by screws such as 10 which serve to compress the packing 11 around the shaft 7 and prevent leakage from the suds container. The shaft 7 is provided with an enlarged cylindrical portion 12 and said portion and the shaft 7 are revolvably mounted within the sleeve 8. The portion 12 is provided with a groove 13 into which projects the end of the screw 14. The screw 14 is mounted in the sleeve 8 and 75 serves to prevent endwise motion of the shaft 7 with reference to said sleeve.

The gear 15 is provided with the hub 16 and said hub is revolvably mounted within the sleeve 8. The shaft 7 is provided with an 80 extension 17 which is revolvably mounted within the hub 16. A washer 18 is secured on the extension 17 by the pin 19. A clutch member 20 is slidably mounted upon the extension 17 and is prevented from turning 85 relative thereto by the key 21 which projects into a keyway formed in the clutch member 20.

The clutch member 20 is moved axially along the extension 17 by the pin 22 which 90 is eccentrically located upon the cylindrical clutch shifter 23. The clutch shifter 23 is revolvably mounted in the casing 24 and is prevented from moving longitudinally by the end of the screw 25 which projects into 95 the groove 26 formed in the shifter 23.

A handle 27 secured to the shifter 23 provides means for turning same and said handle moves over the top 28 of the casing upon which suitable directions with reference to said handle are displayed as shown in Fig. 1.

The member 20 is provided with teeth such as 29 which can be moved into the groove 30 when the cylinder is to be operated by 105 the gear 15.

The casing 24 is provided with axially aligned bearings 31 and 32 in which are revolubly mounted the hubs of the pinions 33 and 34, respectively.

5 The pinion 34 is prevented from moving longitudinally by the end of the screw 35 which extends into the groove 36 formed in the hub of said pinion. The pinion 33 is prevented from moving endwise by its shoulder bearing against the end of the bearing 31 and by the shoulder of the square shaft 37 which extends between the pinions 33 and 34.

10 The clutch member 38 slides upon the square shaft 37 and the left end of said shaft is made cylindrical and is revolubly mounted in a bearing provided in the pinion 33. The clutch member 38 may be shifted along the shaft 37 by the pin 39 formed upon the lever 40 and the latter is made integral with the shaft 41. The shaft 41 extends through a suitable bearing provided in the casing 24 and the handle 42 is secured upon said shaft.

15 Packing 43 is placed around the shaft 41 in order to prevent leakage of oil from the interior of the casing 24. The handle 42 has formed at its lower end three conical depressions 43, 44 and 45 for a purpose hereinafter explained.

20 30 At the top 28 adjacent the handle 42 suitable bearings are displayed for the operation of the handle 42.

25 35 A pin 46 slidably mounted in a hole provided in the casing 24 and pressed upwardly by the spring 47 has a conical point which enters the depressions 43, 44 and 45 for a purpose hereinafter explained.

40 45 In the left side of the hub of the pinion 33 there is loosely mounted a main driving shaft 48 which is cylindrical in cross section and a pin 49 fitting tightly in said shaft and loosely in holes provided in the hub of the pinion 33 serves to form a driving connection between the shaft 48 and said hub.

50 The shaft 37 is provided with a cylindrical enlargement 50 formed integrally therewith at its upper end and said enlargement is revolubly mounted in a bearing provided in the hub of the pinion 34.

55 To the upper end of the enlargement 50 the sleeve 51 is secured by pins such as 52 and said sleeve is prevented from moving endwise by the end of the screw 53 which projects into a groove 54 formed in said sleeve.

60 65 The wringer driving shaft 55 cylindrical in cross section is loosely mounted in a cylindrical hole in the end of the sleeve 51 and a driving connection between said shaft and said sleeve is furnished by the pin 56 which fits tightly in said shaft and loosely in holes provided in said sleeve.

70 75 Tubes such as 57 and 58 may be used to shield the shafts 48 and 55 if desired.

The operation of my improved center housing is as follows:—

70 Power being applied to the shaft 48 the pinion 33 is revolved thereby and this revolves the gear 15. When the clutch member 20 is in the position shown in Fig. 2 the driver 6 will not be revolved but when the handle 27 is moved to the position marked "On" in Fig. 1, the pin 22 moves the member 20 until the tooth 29 enters the 75 groove 30 and then the driver 6 is driven by the gear 15.

75 80 In order to hold the handle 27 in any position to which it may be moved, a pin 57 is slidably mounted in the boss 58 formed on the casing 24 and pressed upwardly, (see Fig. 1), by the spring 59. When the handle 27 is in the position marked "Off" in Fig. 1 the point of the pin 57 is in the depression 60, (see Fig. 2), and when the handle 27 is in the position marked "On" in Fig. 1 the point of the pin 57 is in the depression marked 61, (see Fig. 1.)

85 90 The operator can stop the cylinder at any time by moving the handle 27 to the position marked "Off".

95 When the operator desires to start the wringer, he moves the handle 42 from the position shown by dotted lines to either of the positions indicated by the dotted lines 62 and 63 in Fig. 3.

100 105 If the operator moves the handle to the position indicated by the dotted line 62, the tooth 64 on the clutch member 38 will enter the groove 65 of the pinion 33 and the shaft 55 will be driven in the same direction as the pinion 33.

110 115 If the operator moves the handle to the position indicated by the dotted line 63, the tooth 66 on the clutch member 38 will enter the groove 67 on the pinion 34 and will drive the shaft 55 in the same direction as the pinion 34 is rotating; that is, in a direction opposite to that in which said shaft was driven when it was rotated by the pinion 33.

120 125 It is to be noted that the top 28 may be removed without disarranging any of the working parts. It is further to be noted that the casing 24 and sleeve 8 are secured together on opposite sides of the suds container 5 by bolts such as 68. Hence in assembling my improved center housing, the casing 24 is placed on one side of said suds container with the gear 15 in said casing. The sleeve 8 is then placed on the other side of said suds container and the two parts drawn together by bolts such as 68. The washer 18 and the pin 19 are then to be put in place, which can be readily effected through the opening closed by the plate 28.

130 It is also to be noted that the pinions 33 and 34 are to be put in place through the opening at the top of the casing, the screw 35 to be put in place and then the shafts 130

37, 55 and the sleeve 51 can be placed in position by sliding the shaft 37 through the the central cylindrical hole in the pinion 34. The screw 53 is then to be put in place.

5 Prior to the assembling, the shaft 55 may be connected to the sleeve 51 by the pin 56 but the pin 49 is preferably put in place by passing the shaft 48 upwardly through the bearing 31, then passing the pinion 33 10 into the casing 24, bringing it into relation with the shaft 48 and then inserting the pin 49.

One of the objects of my invention is to arrange the center housing so that these 15 operations of assembling may be readily performed.

While I have shown one preferred form 20 of my invention, it is to be noted that changes may be made therein without departing from the spirit of my invention.

I claim:—

1. The combination with a casing having a pair of aligned bearings and a bevel gear revolubly mounted in said casing, of a pair 25 of bevel pinions meshing with said gear and each having a hub revolubly mounted in one of said bearings, cylindrical shaft bearings formed in said hubs, one of said shaft bearings being larger in diameter than the 30 other, the hub having the larger bearing comprising a groove, a screw in said casing having a point extending into said groove to prevent displacement of the grooved hub from its bearing, a shaft comprising cylindrical portions of different diameters revolubly mounted in said shaft bearings and a square portion extending between said 35 pinions, said square portion being of such cross section that it will pass through the larger but not the smaller of said shaft bearings, whereby the shoulder of said square portion will prevent displacement from its bearing of the hub having the smaller shaft bearing, a sleeve secured to 40 the larger of said cylindrical portions, said sleeve having a groove, a screw mounted in said casing and having a point extending into said groove to prevent axial movement of said shaft, a driven shaft connected to said sleeve, a driving shaft connected to the hub having the smaller shaft bearing, a clutch member comprising teeth slidably mounted on said square portion, said pinions having clutch grooves for the reception 45 of said teeth and means for moving said member to bring said teeth into either of said clutch grooves to couple said driven shaft with either of said pinions.

2. The combination with a casing having 50 a pair of aligned bearings and a bevel gear revolubly mounted in said casing, of a pair of bevel pinions meshing with said gear and each having a hub revolubly mounted in one of said bearings, cylindrical bearings formed in said hubs, one of said shaft bear-

ings being larger in diameter than the other, the hub having the larger bearing comprising a groove, a screw in said casing having a point extending into said groove to prevent displacement of the grooved hub from its bearing, a shaft comprising cylindrical portions of different diameters revolubly mounted in said shaft bearings and a square portion extending between said pinions, said square portion being of such cross section that it will pass through the larger but not the smaller of said shaft bearings, whereby the shoulder of said square portion will prevent displacement from its bearing of the hub having the smaller shaft bearing, a sleeve secured to the larger of said cylindrical portions, said sleeve having a groove and a screw mounted in said casing and having a point extending into said groove to prevent axial movement of said shaft. 85

3. The combination with a casing having a pair of aligned bearings and a bevel gear having a hub, of a pair of bevel pinions meshing with said gear and each having a hub revolubly mounted in one of said bearings, means for driving one of said pinions, driven mechanism, means for driving said mechanism by either of said pinions, a sleeve in said casing comprising a bearing for the hub of said gear, a shaft revolubly mounted in bearings in said sleeve and gear, said gear comprising clutch grooves, a clutch member keyed to and slidably mounted on said shaft and provided with teeth for entering said clutch grooves to couple said shaft and gear and means for moving said member. 95

4. The combination with a casing having a pair of aligned bearings and a bevel gear having a hub, of a pair of bevel pinions meshing with said gear and each having a hub revolubly mounted in one of said bearings, means for driving one of said pinions, driven mechanism, means for driving said mechanism by either of said pinions, a sleeve in said casing comprising a bearing for the hub of said gear, a shaft revolubly mounted in bearings in said sleeve and gear, said gear comprising clutch grooves, a clutch member keyed to and slidably mounted on said shaft and provided with teeth for entering said clutch grooves to couple said shaft and gear and means for moving said member, said casing having an opening permitting the introduction of the hub of said gear into the bearing in said sleeve. 100

5. The combination with a casing having a pair of aligned bearings and a bevel gear having a hub, of a pair of bevel pinions meshing with said gear and each having a hub revolubly mounted in one of said bearings, means for driving one of said pinions, driven mechanism, means for driving said mechanism by either of said pinions, a sleeve in said casing comprising a bearing for the 110

hub of said gear, a shaft revolvably mounted in bearings in said sleeve and gear, said gear comprising clutch grooves, a clutch member keyed to and slidably mounted on said shaft and provided with teeth for entering said grooves to couple said shaft and gear and means for moving said member, said shaft having a groove formed therein and a screw mounted in said sleeve and entering said groove to prevent endwise movement of said shaft.

6. The combination with a casing having a pair of aligned bearings and a bevel gear having a hub, of a pair of bevel pinions meshing with said gear and each having a hub revolvably mounted in one of said bear-

ings, means for driving one of said pinions, driven mechanism, means for driving said mechanism by either of said pinions, a sleeve in said casing comprising a bearing for the hub of said gear, a shaft revolvably mounted in bearings in said sleeve and gear, said gear comprising clutch grooves, a clutch member keyed to and slidably mounted on said shaft provided with teeth for entering said grooves to couple said shaft and gear and means for moving said member, packing and a gland in said sleeve for compressing said packing around said shaft.

In testimony whereof, I affix my signature.

GEORGE C. HOCKENBERGER.
